United States Patent Office

Des. 211,877

Patented Aug. 6, 1968

211,877

COMBINED BATH TUB AND GRAB RAILS

Donald W. Doman, Janesville, Wis., assignor to Kohler Co., Kohler, Wis., a corporation of Wisconsin

Filed Feb. 20, 1968, Ser. No. 10,647

Term of patent 14 years

(Cl. D23—55)

Fig. 1

Fig. 2

Fig. 3

FIG. 1 is a top plan view of a combined bath tub and grab rails showing my new design;

FIG. 2 is a cross sectional view taken on line 2—2 of FIG. 1; and

FIG. 3 is a cross sectional view taken on line 3—3 of FIG. 2.

The dominant features of the design reside in the portions shown in full lines.

I claim:

The ornamental design for a combined bath tub and grab rails, substantially as shown and described.
